US00D997975S

(12) **United States Design Patent** (10) Patent No.: **US D997,975 S**
 Choy (45) Date of Patent: ** Sep. 5, 2023

(54) **DISPLAY SCREEN WITH GRAPHICAL USER INTERFACE**

(71) Applicant: **Becton, Dickinson and Company**,
 Franklin Lakes, NJ (US)

(72) Inventor: **Lauren Marie Choy**, San Bruno, CA
 (US)

(73) Assignee: **BECTON, DICKINSON AND COMPANY**, Franklin Lakes, NJ (US)

(**) Term: **15 Years**

(21) Appl. No.: **29/788,786**

(22) Filed: **Jul. 27, 2021**

(51) LOC (14) Cl. **14-04**

(52) U.S. Cl.

USPC **D14/485**

(57) **CLAIM**

The ornamental design for a display screen with graphical user interface, as shown and described.

DESCRIPTION

The FIGURE is a front view of a display screen with a graphical user interface.

The outermost broken line depicts a display screen and forms no part of the claimed design. The remaining broken lines depict portions of a graphical user interface and form no part of the claimed design.
